UNITED STATES PATENT OFFICE.

STANLEY R. HOWARD, OF EAST MILTON, MASSACHUSETTS, ASSIGNOR TO PNEUMATIC SCALE CORPORATION, LIMITED, OF QUINCY, MASSACHUSETTS, A CORPORATION OF MASSACHUSETTS.

CARTON-FORMING MACHINE.

Application filed May 9, 1927. Serial No. 189,884.

This invention relates to a carton forming machine.

One object of the invention is to provide a novel carton forming machine by which 5 cartons may be formed in a superior, automatic, and economical manner.

A further object of the invention is to provide a novel automatic machine for forming bottom sealed cartons from carton blanks, 10 which is particularly useful in the packaging of goods by automatic machine.

With these objects in view, the invention consists in the carton forming machine, and in the various structures, arrangements and 15 combinations of parts hereinafter described and claimed.

In the drawings illustrating the preferred embodiment of the invention, Figure 1 is a side elevation of the improved carton forming machine; Fig. 2 is a plan view of the parts shown in Fig. 1; Fig. 3 is a front elevation of the carton feeding, folding and side sealing mechanism comprising a part of the present machine; Fig. 4 is a vertical, longitudinal section through a portion of the mechanism shown in Fig. 3 taken on line 4—4 of Fig. 3; Fig. 5 is a partial side elevation of the blank feeding and the side sealing mechanism viewed from the side of the machine 25 opposite that shown in Fig. 1; Figs. 6 and 7 are diagrammatic details illustrating the manner of opening the partially formed carton and of transferring it to a part of the mechanism for sealing the bottom flaps of the 30 carton; Fig. 8 is a detail to be referred to; and Figs. 9, 10 and 11 are diagrammatic views 35 illustrating the operation of the folding and side sealing mechanism.

In general in the present carton forming 40 machine provision is made for folding carton blanks and for sealing the side seams of the blanks as they are folded to form the so-called "knock down" cartons, comprising the flattened tubular body portion having top and 45 bottom flaps projecting therefrom. After the carton blanks have been formed into the knock down cartons, provision is made for opening the knock down cartons and for delivering them to mechanism for sealing the 50 end flaps thereof. In the preferred embodiment of the invention the carton blanks are automatically fed from a bulk supply, to the folding and side sealing mechanism and the various mechanisms in the machine operate

in timed relation to one another whereby 55 during the operation of the machine successive bottom sealed cartons are formed directly from the flat carton blanks.

Referring now to the drawings, the illustrated carton forming machine is designed 60 to operate upon carton blanks of the usual shape shown in Fig. 9. Each blank 12 is creased along the usual fold lines forming panels of which the panels 14 and 20 and the panels 16 and 18 respectively form the opposite 65 sides of the carton. The panel 18 is provided with the usual sealing lap 30, and all of the panels 14, 16, 18, 20 are provided with bottom and top flaps 32, 34, 36 and 38, and 42, 44, 46 and 48 respectively. 70

In the illustrated machine, provision is made for storing the carton blanks in bulk and for automatically delivering successive carton blanks one at a time to a position to be operated upon by the folding and side sealing 75 mechanisms. As illustrated in Figs. 1 and 2, the flat carton blanks 12 are stacked in elevator mechanism indicated generally at 58 and comprising conveyor chains 56 running over lower sprockets 60 on shafts 62 and 80 over upper sprockets 64 on shafts 66, the shafts 66 comprising the driving shafts as will be described. The conveyor chains 56 are provided with shelves 54 upon which the 85 cartons are stacked and which, as the chains are elevated lift the cartons to maintain the uppermost carton in the stack in a position from which it may be withdrawn and fed to the side sealing and folding mechanisms, as will be described. 90

Provision is preferably made for automatically actuating the elevator mechanism to lift the stack of carton blanks and to maintain the uppermost carton blank in a position to be operated upon by the mechanism for transferring it to the side sealing and folding mechanism. For this purpose a feeler finger 78 is mounted in position to normally engage the uppermost blank in the stack when the blank is in a position ready to be withdrawn 95 from the stack, and provision is made for initiating the elevator driving mechanism each time that the feeler finger 78 drops onto the next lower carton blank in the stack following the withdrawal of the uppermost carton from the stack. For this purpose the upper shafts 66 (comprising the driving 100 shafts for the conveyor chains 56) are pro- 105

vided with worm wheels 68 secured thereto and with which cooperate worms 70 secured to a shaft 72 journalled in fixed bearings 74. The shaft 72 is provided with a ratchet wheel 76 with which cooperates a pawl 84 pivoted upon a pawl arm 82 secured in a sleeve 80, itself rotatably mounted upon the shaft 82. The feeler finger 78 is also secured upon the sleeve 80 so that when the feeler finger drops after the uppermost carton blank has been withdrawn from the stack, the pawl is reset ready to advance the ratchet wheel a succeeding step. The mechanism for advancing the pawl and the ratchet wheel includes a cam arm 86 pivoted at its upper end upon the pawl arm 82 and provided with a forked lower end arranged to straddle a cam shaft 88. The cam shaft 88 is constantly driven at a predetermined speed herein shown by a chain 94 running over a sprocket 96 on the shaft 88 and which chain 94 is driven as will be described in timed relation to the mechanism for sealing the bottom flaps of the cartons. In the operation of the mechanism thus described, when the feeler finger drops, resetting the pawl with relation to its ratchet, the cam arm 86 moves radially downwardly on the cam shaft 88 and brings a cam roll 100 pivotally secured to said cam arm into the path of an abutment formed on a cam 102 secured to the shaft 88, and as the cam 102 revolves the engagement of the abutment 103 with said cam roll 100 raises the cam arm 86 and consequently rocks the pawl arm 82 and pawl 84 in a counter clockwise direction, as seen in Fig. 1, thus turning the ratchet wheel 76 in the same direction, and through the worm 70 and worm wheels 68 turning the shafts 66 in a direction to raise the elevator chains 56 and to bring the next uppermost carton blank into desired position from which it may be withdrawn from the stack.

In the illustrated machine the individual blanks are successively transferred from the top of the stack in the elevator 58 by a pair of suction transfer members 104, 106, and are deposited by said transfer members on a pair of constantly driven parallel feed belts 108, 110. The transfer members 104, 106 preferably comprise hollow members provided on their forward ends with suction cups 112, 114. The hollow members 104, 106 are preferably connected to a suitable source of suction (not shown) whereby after the suction cups 112, 114 contact with the surface of the uppermost blank in the stack the suction retains the blank in such position and permits the transfer members 104, 106 to lift the blank from the stack and feed it forwardly to deposit it upon the feed belts 108, 110.

An oscillating movement is imparted to the transfer members 104, 106 to effect the withdrawal of the uppermost blank from the stack and for depositing it upon the belts 108, 110, and as herein shown the transfer

members 104, 106 are pivoted to the lower ends of arms 116 depending from and secured to a rock shaft 118. The rock shaft 118 is rocked to impart to the transfer members the necessary horizontal movements to permit them to perform their intended functions, by a cam 130 upon the shaft 88, through suitable linkage connections including an arm 120 secured to the shaft 118 and pivoted at its other end to one end of a link 122. The link 122 is pivotally secured to one arm of a bell crank cam lever 124 pivoted at 126 to the frame of the machine. The other arm of the bell crank lever 124 is provided with a pivoted cam roll 128 which cooperates with a cam path formed in the cam 130.

In order to control the vertical position of the suction cups 112, 114 of the transfer members during the above described horizontal movement thereof, the transfer members 104, 106 have pivotally secured to their rear ends links 136 connected to arms 132 secured upon a rock shaft 134. The rock shaft 134 is rocked by a cam 148 through linkage connections including an arm 138, a link 140 connected to one arm of a bell crank lever 142, pivoted at 144 to the machine frame, and having the other arm of the bell crank lever 142 provided with a cam roll 146 which cooperates with a cam groove in the cam 148. The cam 148 is secured to the cam 88 and is of such design that through the connections described the vertical position of the suction cups 112, 114 are controlled to enable the blank to be withdrawn from the stack and deposited upon the feed belts 108, 110.

Provision is made for positively feeding the blank after it has been thus deposited upon the feed belts 108, 110 in order to overcome the grip of the suction cups 112, 114 upon the blank and to thereby permit the transfer members to be returned to a position to engage the next succeeding blank in the stack, and for this purpose pivotally mounted idler feed rolls 168, 170 and 172 are dropped down to engage the upper surface of the blank and to thereby cooperate with driven feed rolls 162, 164 and 166 to feed the blank forwardly overcoming the gripping of the suction cups upon the blank. The feed rolls 162, 164, 166 are secured upon a shaft 160 and the latter is driven by pulleys 156 and 158 upon the shaft and over which the feed belts 108, 110 run. The feed belts 108, 110 also run over pulleys 150, 152 mounted upon a constantly driven shaft 154. The idler feed rolls 168, 170 and 172 are pivotally secured on the forward ends of arms 174 pivoted upon a rock shaft 176. The rock shaft 176 has secured to it arms 178 which normally engage the lower surfaces of abutments 180 formed on the arms 174. The idler feed rolls 168, 170 and 172 are raised and lowered at the desired times by a cam 182 secured to the constantly rotating shaft 88 through linkage

connections including an arm 182 secured to one end of the rock shaft 176, a link 184 connected to a cam lever 186 pivoted at 188 on the machine frame, and having a cam roll 190 5 engaging a cam groove in the cam 132.

After the idler feed rolls have been lowered onto the driven feed rolls, the blank is fed forwardly, first by both the feed rolls and the moving belts 108 and 110 and then by the belts 10 alone after the rear end of the blank passes through the feed rolls. During this forward movement the blank is positioned over fixed folding members 192 and 194 located within and parallel to the feed belts 108 and 110 and 15 the forward movement of the blank is stopped by the engagement of the forward end of said blank with upwardly projecting stop fingers 196 and 198 formed on the forward ends of the folding members 192 and 194. 20 During the forward movement of the blank, provision is made for applying glue or other adhesive to the lower surface of the side sealing tab 30 of the blank. To this end, as the blank is fed forwardly, the lower surface 25 of the tab 30 engages a glue roll 200 arranged to engage a constantly driven transfer roll 202 operating in a glue tank 204, the transfer roll thus operating to drive the glue roll and to coat its surface with glue, which 30 the glue roll, in turn, transfers to the bottom surface of the tab 30, as indicated at 52 in Figs. 9, 10 and 11. 35 Provision is made for folding the outer side members 18 and 20 of the blank upwardly at right angles to the remaining portion of the blank after the blank has been brought to rest by the engagement of its forward end with the stop members 196 and 198. For this purpose as herein shown, fixed folding members 192 and 194 are located in a position such that when the blank is fed into 40 position over them they are beneath the inner portions of the side members 18 and 20 of said blank with their inner edges in line with the creases 22 and 26 formed between the side members 18 and 14 and 20 and 16, respectively. With the blank in this position, a folding plate 206 is moved downwardly to engage the side members 14 and 16 of the 45 blank and force them downwardly between the fixed folding members 192 and 194, thus folding the side members 18 and 20 upwardly at right angles to the side members 14 and 16 at the creases 22 and 26, as indicated in Fig. 50 10. During its downward movement, the blank is guided between vertical guide plates 208 and 210 secured to the fixed folding members 192 and 194 and comes to rest on a fixed table 212, (Fig. 4). 55 In order to impart the desired movement to the folding plate 206, it is secured to one end of a curved arm 214 secured at its other end to a rock shaft 216 journaled in bearings 218. An arm 220 is also secured at one end 60 to the rock shaft 216 and has pivotally se-

cured to its other end a link 222, the other end of which is pivotally secured to one-arm of a bell crank cam lever 224 pivoted at 226 to the machine frame. A cam roll 228 secured to the second arm of the bell crank cam lever 70 75 engages a cam path formed in the cam 148 secured to the shaft 88. It may be seen from an inspection of Figs. 3 and 5 that the arm 220 and the bell crank cam lever 224 oscillate in mutually perpendicular planes. The link 222 connecting these members is provided on its opposite ends with universal joints 230 to permit it to accommodate itself to the different positions of these members.

After the blank having the members 18, 20 folded up at right angles to the remainder of the blank, comes to rest on the table 212, provision is made for folding the members 18, 20 inwardly through another angle of 90° until they are folded down on the remainder 80 of the blank. For this purpose, folding rolls 232 and 234 journaled in the inner ends of slides 236 and 238 slidably mounted in guideways 240 and 242 secured to the table 212 are arranged to be moved inwardly to engage the side members 18 and 20 and fold them down in the manner desired. The mechanism for effecting such movement of the rolls includes cam levers 244 and 246, provided with forked upper ends arranged to engage pins 248 and 250 secured to the slides 236 and 238, and which are pivoted at 252 and 254, respectively, to fixed brackets 256 and 258. The cam levers 244, 246 are oscillated by cam rolls 260 and 262 secured to the lower ends thereof, 90 which are arranged to yieldingly engage cam paths formed in cylindrical cams 264 and 266 secured to the constantly rotating shaft 88.

In order that the outer portion of the side member 20 may be secured to the flap 30, the cam grooves in the cams 264 and 266 are so shaped that the roll 232 engages the side member 18 to fold it downwardly before the side member 20 is folded down by the roll 234. Consequently, the outer portion of the side member 20 is folded down onto the glued surface 52 of the tab 30 and pressed against said glued surface to be firmly affixed thereto by the roll 234, and the blank is thus formed 100 into a tubular knockdown carton.

After the carton blank has thus been formed into a knockdown carton, provision is made for opening it and presenting the open carton to mechanism for sealing the bottom flaps of the carton. The latter mechanism is indicated generally at 267 and the details of construction and operation except as hereinafter pointed out, may and preferably will comprise the bottom sealing mechanism illustrated and described in the United States patents to S. R. Howard No. 1,342,047, June 1, 1920, and W. S. Scales No. 767,445, August 16, 1904. A sufficient portion of such bottom sealing mechanism has been herein shown to 115 120 125 130

enable the present invention to be clearly understood, but inasmuch as the details of such bottom sealing mechanism of itself form no part of the present invention, reference is 5 made to said U. S. Patents Nos. 1,342,047 and 767,445 for a more complete description and illustration thereof.

Referring now particularly to Fig. 4, as 10 illustrated therein the mechanism for opening the knockdown carton formed as above described and presenting it to the bottom sealing mechanism 267 includes a feed roll 268 secured to a constantly driven shaft 270 located adjacent the forward edge of the table 15 212, and with its top at substantially the same level as the top of the table.

In the operation of the machine, after the 20 flat carton blank has been formed into the knockdown carton, the bottom flaps project beyond the table 212 and are positioned over the feed roll 268, and at this time upper feed rolls 272 are swung downwardly from the full line position to the dotted line position, shown in Fig. 4, to engage the knockdown 25 carton between the rolls 272 and 268 and feed it forwardly.

As the feed rolls 268 and 272 feed the knockdown carton forwardly, it passes over and around a feed drum 302 secured to a 30 constantly driven shaft 304, being guided around said drum by fixed guide members 306 and fed by feed rolls 308 and 310 cooperating with said drum. The feed rolls 308 and 310 are pivotally secured to arms 312 and 314 pivotally mounted on a fixed shaft 316, and springs 318 extended between each pair of arms 312 and 314 urge said arms inwardly against the drum 302 thus engaging the carton between said rolls 308 and 310 and 40 the drum 302 and feeding it forwardly and downwardly between the drum and the guide members 306, and then downwardly between the guide members 306 and 320, the latter being located beneath the forward edge of the drum 302 in the rear of the lower portion of the guide members 306. After passing downwardly between the guide members 306 and 320, the carton drops into a pocket 322 and comes to rest therein with its 50 bottom portion resting on adjustable supports 324 (Figs. 3 and 4) located below said pocket. The carton is guided into the pocket 322 in the position indicated in dotted lines at 326 in Figs. 3 and 6, by the engagement of 55 its edges with recesses 328 and 330 formed at the sides of said pocket.

The mechanism for swinging the rolls 272 into and out of engagement with the feed rolls 268 includes a rock shaft 276 upon which are 60 mounted arms 274. The rolls 272 are secured to one end of the arms 274. The arms 274 are arranged to have limited rotative movement with relation to the rock shaft, and for this purpose keys 278 secured in the shaft 65 276 extend into recesses 280 formed in the

hubs of the arms 274. Arms 282 are secured at one end to the rock shaft 276 adjacent the arms 274 and springs 284 taking between spring seats 286 formed at the other ends of the arms 282 and seats 288 formed on the 70 arms 274, normally hold the keys 278 against the end of the recesses 280 but permit the arms 274 to yield when the rolls 272 engage the rolls 268. The rock shaft 276 is arranged to be rocked by a cam 300 upon the shaft 88, 75 through linkage connections including an arm 290 (Fig. 5) secured to the rock shaft, a link 292, bell crank cam lever 294 pivoted at 296 on the machine frame, and having a cam roll 298 which cooperates with a cam 80 path formed on the cam 300.

After the knockdown carton reaches the described position in the pocket 322, provision is made for opening it and for presenting the opened carton to the bottom sealing 85 mechanism. The latter mechanism includes a device for operatively supporting the opened carton while the flap closing and sealing operations are being performed, and as shown in Figs. 1, 2, 6 and 7, such device comprises the carton holding pocket 332 and the block 333, the latter being one of the usual four intermittently rotated blocks of the Scales and Howard patents above referred to, and upon which the carton is placed after 90 having been received in the pocket 332. In Fig. 8 a modified form of carton receiving pocket 335 is shown, which is designed to operatively support the opened carton during 95 the flap closing and sealing operations, and which is mounted upon the usual intermittently rotated spider 337 of the known bottom sealing mechanisms such as illustrated in the Scales and Howard patents above referred to. 100

In order to open the carton and transfer 105 it from the pocket 322 to the pocket 332 of the bottom sealing mechanism as shown in Figs. 1, 2, 6 and 7, a knife 334 is arranged to be moved upwardly and inserted between the bottom flaps of the knockdown carton and then up into the interior of the same. Provision is then made for moving the knife 110 forwardly to transfer the carton to the pocket 332 of the bottom sealer, and the knife is then moved first downwardly to be withdrawn 115 from the carton and then rearwardly to its starting position. During this forward movement the carton is opened, as will be described, by the cooperation of the knife movement and the walls of the pocket 322 with 120 the carton.

The mechanism for operating the knife 334 is arranged to cause the insertion of the knife into the knockdown carton in a manner such that the knife is positioned in the rear 125 of the crease 28 between the tab 30 and the side member 18 of the carton in the position indicated in dotted lines in Fig. 6. It may be seen from an inspection of Figs. 2 and 9 that the bottom flaps 34 and 38 of the carton are 130

shorter than the remaining pair of bottom flaps 32 and 36. The flaps 32 and 36 serve to engage the rods 324 to support the carton in the pocket 322, and in such position, as shown in Fig. 4, the upper end of the knife, 5 as the latter moves rearwardly, will pass under the flap 38 and engage the inside of the flap 36 so that when the knife is moved upwardly it is caused to enter the carton between the flaps 36 and 38. The knife 334 is secured to a slide 336 slidable in vertical slideways 338 and actuated by a lever 340 pivoted at 342, having at its forward end a slot 344 engaging a pin 346 secured to the slide 336. A link 348 is pivoted to the lever 340 and also to the lower end of a yoke 350 which embraces and is mounted to slide vertically on the cam shaft 88 and a shaft 352 above said cam shaft 88. A cam roll 354 20 pivotally secured on the yoke 350 engages a cam groove formed in a cam 356 secured to the cam shaft 88 to impart vertical movements to the knife through the mechanism described. In order to impart desired horizontal movements to the knife, the slideway 338 is secured to a slide 358 mounted to slide on fixed horizontal slideways 360 and actuated by a bell crank cam lever 362, pivoted at 364, provided with a cam roll 366 engaging a cam 30 path in a cam 368 secured to the cam shaft 88, and provided on its other arm with a slot 370 which engages a pin 372 secured to the slide 358.

In the operation of the mechanism, after the knife has been raised and inserted into the carton in the pocket 322, it is moved forwardly and the side members 18, 20 of the carton are engaged by the front walls 374 and 376 of the pocket 322. The cooperation of the movement of the knife and carton with the walls 374 and 376 causes the carton to open up in the manner indicated in full lines at 378 in Fig. 6. As the knife continues to move forwardly, the carton passes out of the pocket 322 through an opening formed between parallel forward extensions 380 and 382 of the walls 374 and 376 and is delivered by the knife into the particular pocket 332 or 335 of either of the bottom sealing mechanisms illustrated in Figs. 2, 6 and 7 or Fig. 8, respectively. As previously pointed out, the pocket 332 is arranged to receive the carton and square it up prior to its delivery onto a forming block, where the bottom flap closing and sealing operations are performed during the intermittent rotation of the block and carton in accordance with the usual operation of these known bottom sealing mechanisms. The carton pocket 335 is, as has been stated, adapted 60 to receive the carton, square it up, and support it during the intermittent rotation of the spider (see Fig. 8) while the usual bottom flap closing and sealing operations are performed.

During the opening of the carton the latter assumes the positions successively represented in dotted lines in Fig. 7 at 384 and then that indicated in full lines at 386 in Fig. 7. The knife continues to move forwardly until the carton is in the position indicated in dotted lines at 388 in Fig. 7 with its side member 18 against the forward wall 390 of the pocket 332. When the carton reaches this position, the right hand portion of its side member 16 75 springs under a rear extension 392 of the pocket 332 (see Fig. 7). Thereafter the left hand side wall 394 of the pocket 332 is swung in a clockwise direction, viewing Fig. 7, by the usual form of operating mechanism (not shown) functioning to square up the carton 80 in the pocket so that it may subsequently be presented to the forming block in correct alignment.

When the bottom sealing mechanism embodies the spider and pocket illustrated in Fig. 8, the carton passes through analogous successive stages in being opened, and eventually is delivered by the knife into the pocket where it is squared up and operatively supported during the bottom flap closing and sealing operations.

Inasmuch as the remaining details of construction and operation of the bottom sealing mechanism may and preferably will comprise that disclosed in the Howard and Scales patents above referred to, further description and illustration of such details are omitted, and for the purposes of the present invention it will be understood that the bottom sealing mechanism delivers the successive cartons 95 in a condition with their bottom flaps folded to close the bottom of the carton and sealed.

From the description thus far it will be observed that the present machine as illustrated herein operates to form cartons having 100 their bottom flaps folded and sealed to close the bottom of the carton, directly from flat carton blanks in an automatic and highly efficient manner, eliminating handling and other uneconomic manufacturing operations.

While the preferred embodiment of the invention has been herein illustrated and described, it is to be understood that the invention may be embodied in other forms within the scope of the following claims.

Having thus described the invention, what is claimed is:

1. In a machine of the character described, the combination with bottom sealing mechanism, of means for feeding a flat carton blank 120 from a bulk supply, means for automatically sealing the side seam of the carton, and means for automatically opening the sealed carton and for delivering it in operative position to the bottom sealing mechanism.
2. In a machine of the character described, in combination, flap sealing devices, means for folding a flat carton blank to form a collapsed carton, means for adhesively sealing the side seam and means for delivering the 130

- sealed carton in open position to said flap sealing devices.
3. The combination with mechanism for sealing the bottom of an open carton, of a container for holding a bulk supply of carton blanks in flat form, and devices for automatically withdrawing successive carton blanks, sealing the side seams thereof, and presenting them in opened condition to the bottom sealing mechanism.
4. The combination with bottom sealing mechanism for sealing the bottom flaps of a carton, of an automatic feed mechanism for a supply of flat carton blanks, and means for folding the carton blanks, sealing the side seams and opening the sealed cartons prior to their presentation to said bottom sealing mechanism.
5. In a carton forming machine, in combination, carton opening means, including a member adapted to be inserted into the carton and actuating means therefor, means for operating upon carton blanks to fold the same and seal the side seams to form knockdown cartons, and means for feeding the knockdown cartons thus formed to present them to said carton opening means.
6. In a carton forming machine, in combination, a holder for a supply of flat carton blanks, folding and side sealing mechanism, mechanism for automatically positioning the cartons in the supply in predetermined relation to the folding and side sealing mechanism, carton blank feeding mechanism, and mechanism for opening the knockdown cartons after the side seams have been sealed.
7. In a carton forming machine for use with bottom sealing mechanism, in combination, carton blank feeding mechanism, fold-
- ing and side sealing mechanism for operating upon successive blanks to form knockdown cartons, automatically operated carton opening means, and means for feeding the open cartons to present them in operative relation to the bottom flap closing and sealing mechanism.
8. In a carton forming machine, in combination, mechanism for feeding successive carton blanks from a bulk supply, transferring mechanism for transferring the carton blank to a position in predetermined relation to folding devices, adhesive applying mechanism for applying adhesive to the side sealing tab during such transfer, folding devices for folding down portions of the carton blank to form a knockdown carton and for sealing the side seam, carton opening means including a reciprocating knife member, and means for feeding the knockdown carton to present it in operative relation to said knife member.
9. In a carton forming machine in combination, a carton receiving pocket, mechanism for withdrawing flat carton blanks from a bulk supply and for folding and sealing the side seams thereof to form knockdown cartons, and devices for opening each knockdown carton and transferring it to the aforesaid pocket, said mechanisms and devices operating in timed relation to one another.
10. The combination with mechanism for sealing the end flaps of a carton, of feeding mechanism for feeding separate flap carton blanks, and mechanism for sealing the side seams of said carton blanks, all of said mechanisms operating in timed relation.

In testimony whereof I have signed my name to this specification.

STANLEY R. HOWARD.
